UNITED STATES PATENT OFFICE.

WILLIAM M. SCHOLL, OF CHICAGO, ILLINOIS.

FELT PAD.

1,382,678.

Specification of Letters Patent. Patented June 28, 1921.

Application filed August 28, 1916. Serial No. 117,210.

To all whom it may concern:

Be it known that I, WILLIAM M. SCHOLL, a citizen of the United States, residing at Chicago, in the county of Cook and State of Illinois, have invented certain new and useful Improvements in Felt Pads, of which the following is a specification.

My invention relates to pads for foot-protection and the like; and one of its objects is 10 to provide a corn or bunion pad of felt or similar fibrous homogeneous material, that is simple in construction, formed to afford advantageous structure for use in connection with certain foot ailments, and suitable for 15 effective practice of modern treatment methods.

In the embodiments of my invention shown in the drawings,

Figure 1 is a plan view of one of my pads; 20 Fig. 2 is a section on line 2—2 of Fig. 1 thereof;

Fig. 3 is a bottom plan view thereof;

Fig. 4 is a section on line 4—4 of Fig. 3.

The pads embodying my invention are 25 made of felt, or similar fibrous, homogeneous material having considerable resiliency, and each pad is made of a single piece of uniform density. Each pad preferably is 30 ovate form in plan, and has, as shown in Fig. 1, a convex crown or upper surface 11 curved smoothly in all parts and in all directions. The crown preferably rises rather abruptly as at 12 close to the perimeter and curving rather rapidly as at 13 inwardly 35 from the ovate perimeter 14, and the pad body is preferably tapered in section, the elevation of the pad near one end being greater than near the other. Each pad has in its under side a shallow elongated recess 40 or pocket 15, preferably ovate or ellipsoidal in plan and having its concaved surface curving gradually and smoothly from the perimeter. The flat area 16 of the under side of the pad, intervening between the 45 perimeters of the recess and the crown, is preferably narrow at the sides of the pad and relatively longer near the ends of the pad.

At a suitable point near the crest of the 50 recess 15 thus provided I form a pressure-relief opening 18, cut straight through the fibrous material, and preferably having its edges sharply meeting the crown surface 11. Further I prefer that the inwardly facing 55 portion of the opening 18 be further re-

cessed, as at 19, to provide a tapering small recess intervening between the major recess 15 and the opening 18.

As illustrated in all of the views it is my preference that the walls of the pad should 60 be thicker adjacent one end of the recess 15 than the other, the difference of thickness varying to suit the demands in different pads, so that in use, localization of shoe-pressure through the pad on one portion 65 of the foot may be made greater to aid in the relief of pressure on the other portions of the foot that are covered by the pad. Also, as indicated in the several figures showing typical forms, the size of the main 70 recess 15 with respect to the outer perimeter of the pad may be varied, and other changes in proportion and specific detail may be made.

All of the curved surfaces are preferably 75 cut surfaces, so exposing "skinless" or raw portions of the felt body, for softness and for advantageous frictional qualities.

In the use of my pad for the treatment of 80 corns, calluses and other sensitive conditions of the foot, the pad used should, of course, be adequate in size to cover substantially the whole affected area and a relatively non-sensitive portion surrounding it, and a pad of greater or less taper, and of 85 more or less thickness will be selected as best may fit the surface to be treated. Usually it is worn next the foot, but may be placed over the stocking. The opening 90

18 is located to cover the most sensitive portion of the area where all pressure is to be relieved, and the thickest portion of the pad, near one end thereof, is brought to bear on a relatively unaffected portion of the foot, usually the area in rear of the affected area. 95 The smooth contours, free from seams, wrinkles or other uncomfortable protuberances, makes the pad one that may most comfortably be employed and its soft cut-surface, of the crown especially, coacts with the shoe or stocking to hold it in position. Where treatment of the corn or other center of irritation with some medicament is desired, the construction having a tapering recess 19 intervening between the opening 100 18 and the main recess 15 is especially desirable as this space will receive a body of medicated cotton, or salve, or other material, and will tend to retain it against bodily escape through the opening 18, without, 105

110

however, causing undue thickening of the pad owing to the presence of the medicament.

While I have herein described in some detail a particular embodiment of my invention it will be apparent that changes in the details thereof may be made without departure from the spirit of my invention and within the scope of the appended claim.

10 Having described my invention, what I claim is:—

A pad for foot treatment, comprising a body of felt without seams or interruptions, of ovate shape in plan and smooth curva-

tures on its crown surface, said body having 15 a recess in its under surface and an opening from said recess to the crown surface, there being a tapering minor recess intervening between the inner edges of said opening and the major recess.

20

In testimony whereof I hereunto set my hand in the presence of two subscribing witnesses.

WILLIAM M. SCHOLL.
